UNITED STATES PATENT OFFICE.

EUGENE DE KLEIST, OF NORTH TONAWANDA, NEW YORK.

AUTOMATIC MUSICAL INSTRUMENT.

SPECIFICATION forming part of Letters Patent No. 677,769, dated July 2, 1901.

Application filed June 18, 1900. Serial No. 20,678. (No model.)

To all whom it may concern:

Be it known that I, EUGENE DE KLEIST, a citizen of the United States, residing at North Tonawanda, in the county of Erie and State 5 of New York, have invented new and useful Improvements in Automatic Musical Instruments, of which the following is a specification.

This invention relates to a self-playing piano or similar instrument in which the sound-producing devices are operated by pneumatics controlled by valves which in turn are operated from a rotary pin-barrel.

The principal objects of my invention are 15 to simplify the construction and reduce the cost of such instruments and to provide a pneumatic-actuating mechanism which is prompt and sensitive in action and not liable to bind or get out of order and in which leakage or waste of air is reduced to a minimum, thus rarefying the air in the pneumatics to the maximum degree, obtaining a prompt and powerful action of the same, and requiring correspondingly less power to operate them.

20 In the accompanying drawings, consisting of two sheets, Figure 1 is a transverse vertical section of my improved piano. Fig. 2 is a similar section, on an enlarged scale, of the exhaust-chamber or wind-chest and adjacent 25 parts, showing the vent of one of the pneumatics open. Fig. 3 is a similar section of the same parts and the pin-barrel, showing one of the exhaust-valves open and the corresponding vent-valve closed. Fig. 4 is a 30 fragmentary vertical longitudinal section in line 4-4, Fig. 3. Fig. 5 is a fragmentary front view of the exhaust-chamber, the vent-valves, and their actuating rods or stickers, one of the vent-valves and the corresponding flexible tube being omitted.

Like letters of reference refer to like parts in the several figures.

35 A is the case of the instrument; b, one of the strings; b', the corresponding hammer, and b² the vertically-movable wippen of the same hammer.

The piano-action forms no part of my invention and may be of any suitable or well-known construction.

40 The wippen of each hammer is operated by a motor-pneumatic C, consisting, preferably, of a small bellows the hinged lower board of

which is connected with the wippen by a vertical rod or sticker c. These motor-pneumatics are arranged in horizontal rows below 55 the piano-action and secured to the under side of longitudinal supporting-bars D, as shown in Fig. 1.

E is a horizontal wind-chest or exhaust-chamber arranged lengthwise in the case A 60 and connected by a pipe e with a suction bellows or pump F, whereby the air is exhausted from said chamber. This bellows may be operated by an electric motor F' or other suitable means.

65 g represents a series of narrow valve-chambers arranged side by side above the exhaust-chamber E and communicating therewith by ports or passages g', which are controlled by upwardly-opening valves g², arranged in said 70 valve-chambers. Each of the motor-pneumatics C is connected with one of said valve-chambers by a duct or passage h, communicating with the top of the valve-chamber, so that when the corresponding valve g² is 75 opened the air is exhausted from said valve-chamber and the passage h and the motor-pneumatic connected therewith, thereby collapsing the pneumatic and raising the sticker c and actuating the corresponding hammer b' 80 or equivalent member. The exhaust-valves g² are operated from a pin-barrel I by horizontal levers J, arranged above the barrel, and vertical rods K. The barrel is journaled horizontally in the front portion of 85 the piano-case and driven by any suitable means and is provided with the usual pins and staples i i', which actuate the levers J. The latter are pivoted between their ends to the under side of a longitudinal support- 90 ing-bar j and are provided at their rear ends with vertically-adjustable screws or stems j', which bear upon the upper ends of the rods K and depress the same when the corresponding lever is rocked. The rods K pass through 95 openings formed in the top of the valve-chambers g, and their lower ends bear upon the rear arms of the exhaust-valves g², so that when a rod is depressed it opens the corresponding valve. The exhaust-valves are automatically closed by springs k.

100 Each valve-chamber g is provided at its top with a vent tube or passage l for admitting the external atmosphere to said chamber and

the motor-pneumatic and allowing the latter to expand. The admission of air into these vent-tubes is controlled by valves l' , applied to the lower portion of the rods K and adapted 5 to close against the open upper ends of said tubes when the rods are depressed. The vent-valves l' are vertically adjustable on their rods, and for this purpose the lower portion of each rod preferably consists of a screw-threaded stem l^2 , as shown, and the vent-valve is provided centrally with a screw-threaded opening which engages with said stem, so that the valve is adjusted toward or from the upper end of the vent-tube l by turning it on 10 its stem. These valves are located so closely to the upper ends of the vent-tubes that they close the same and exclude the atmosphere as soon as the exhaust-valves are opened or begin to open, so that the leakage of the atmosphere into the valve-chambers when an 15 exhaust-valve is open is reduced to a minimum, while at the same time a vent of sufficient size is provided for the atmosphere to insure a prompt expansion of the motor-pneumatic as soon as the corresponding exhaust-valve is closed. By this construction an effective vacuum is obtained and the pneumatics are quickly and forcibly collapsed, and as the leakage of the atmosphere through the 20 vent-tube is but slight and momentary practically the full power of the suction-bellows F is obtained, and the instrument can be driven by a comparatively small motor.

The pins and staples of the barrel I are 25 made of different heights or lengths in a well-known manner, those pins which are arranged closely together and produce rapid passages of a piece of music being comparatively short and effecting a shorter stroke of the valve- 30 actuating levers J than the longer pins. The space between the upper ends of the vent-tubes l and their valves l' when open is less than the stroke of the levers J, produced by the long pins of the barrel, and to compensate for the variable stroke of these levers 35 and the rods K, which carry said vent-valves, the vent-tubes are made flexible or yielding, so that they are free to collapse, more or less, and accommodate themselves to the irregular 40 movements of the levers.

l^3 represents springs which are arranged in the vent-tubes l and which serve to expand the same.

The motor-pneumatics in expanding tend 55 to exhaust the air from the passages h and valve-chambers g , causing the vent-valves l' to adhere to the ends of the vent-tubes l and interfering with the action of the instrument. To prevent this, each rod K is provided with 60 a return-spring m , which lifts the rod to its normal position immediately after having been depressed and released by the corresponding lever J, thereby positively withdrawing the vent-valve from the vent-tube. 65 This return-spring is applied to the upper end of the valve-rod and bears at its lower end upon a stationary bar m' and at its upper

end against a transverse pin m^2 of the rod. Each of the latter is provided below the supporting-bar with a stop-pin m^3 , which limits 70 the upward stroke of the rod by striking said supporting-bar.

The operation of my improved instrument is as follows: Upon setting the suction-bellows F in motion the same produces a partial 75 vacuum in the exhaust-chamber E. When a pin or staple of the barrel I rocks a lever J, the latter depresses the corresponding rod K, which in turn opens the corresponding exhaust-valve g^2 and causes the vent-valve l' to 80 close the vent-tube l . The atmosphere is now shut off from the corresponding valve-chamber and the air is exhausted from said chamber and the motor-pneumatic C connected therewith, thereby contracting the latter and causing the same to actuate the corresponding hammer b' and producing the tone represented by the same. As soon as the actuated lever J clears the pin of the barrel the corresponding rod K is raised by its 85 spring m , thereby opening the vent-valve l' and allowing the exhaust-valve to close. The suction-bellows F is now cut off from said motor-pneumatic and the atmosphere is permitted to enter the same through the vent-tube l , valve-chamber g , and the duct h , causing the pneumatic to expand and allowing the hammer-operating devices to return to their normal position. In practice there must be a slight play or clearance between the 90 trip-levers J and the rods K in order to allow the exhaust-valves g^2 to close fully, and a slight clearance is also desirable between the valves g^2 and the headed lower ends of the valve-stems l^2 , which open said valves, so that 95 the normally open vent-valves l' are closed or begin their closing movement a moment in advance of the opening movement of the exhaust-valves for the purpose of preventing leakage of air through the vent-tubes as 100 much as possible. As hereinbefore stated, the motor-pneumatics C in expanding tend to produce a partial vacuum in the passages h and the valve-chambers g , which causes the vent-valves l' to adhere to the upper ends of 105 the vent-tubes l . When this occurs, the next pin of the barrel I, which trips the corresponding lever J, has no effect upon the corresponding hammer b' and the music is imperfectly rendered. The spring k of each 110 exhaust-valve causes the stem l^2 of the vent-valve to rise in closing said exhaust-valve; but owing to the above-described clearance between the parts the exhaust-valve closes 115 fully before raising said stem sufficiently to open the vent-valve. In order to insure the opening of the latter under all conditions, the rod K is provided with the spring m , which acts upon the vent-valve independently of the closing-spring k of the exhaust-valve. The spring m lifts the corresponding 120 rod K away from the exhaust-valves g^2 , allowing the latter to close firmly, and as soon as the finger of the lever J clears a pin or 125
